UNITED STATES PATENT OFFICE.

LEMUEL P. COULTER, OF HUNTINGTON PARK, CALIFORNIA.

GAS BURNER.

Application filed February 18, 1922. Serial No. 537,529.

To all whom it may concern:

Be it known that I, LEMUEL P. COULTER, a citizen of the United States, residing at Huntington Park, in the county of Los Angeles and State of California, have invented new and useful Improvements in Gas Burners, of which the following is a specification.

This invention relates to improvements in 10 liquid fuel burners.

The principal object of this invention is to produce a burner which will use a liquid fuel, vaporize the same and then burn as a gas without giving off a carbon deposit.

15 Another object of this invention is to produce a burner of this type which is simple in construction, free from complicated parts and consequently, easy to operate, and economical to manufacture.

20 A further object of this invention is to produce a burner which may be used in any ordinary cook-stove or the like thereby doing away with the usual coal or wood fuel.

Other objects and advantages will be apparent during the course of the following description.

In the accompanying drawings forming a part of this specification and in which like numerals are employed to designate like parts throughout the same,

30 Fig. 1 is a cross-section of a cook-stove fire-box having my invention attached thereto,

Fig. 2 is a side elevation of my burner,

35 Fig. 3 is a top plan view of my burner, Fig. 4 is a cross-section taken on the line 4-4 of Fig. 5,

Fig. 5 is a cross-section taken on the line 5-5 of Fig. 4, and

40 Fig. 6 is a cross-section taken on the line 6-6 of Fig. 4.

In the drawings wherein for the purpose of illustration is shown a preferred embodiment of my invention, the numeral 5 designates a fire-box of the ordinary cook-stove having the usual grate 6, while the numeral 7 designates a liquid fuel tank having an outlet pipe 8 attached to the bottom thereof. This pipe is of an extremely small diameter and is known to trade as hollow wire. At 45 9 I have shown a pipe entering the top of the tank which pipe is adapted to be connected to an air pressure pump for the pur-

pose of placing air pressure on the top of the liquid fuel. On the pipe 8 I place a 55 shut-off valve 11 and preferably place the same some distance away from the stove. This pipe 8 is carried through the side wall of the stove and connects through the medium of a union 12 to a retort pipe 13 supported above and resting on the burner as a whole, this pipe 13 after passing across the top of the burner extends downwardly as shown at 14 and enters a T connection with 60 in which is a needle valve controlled through the medium of a rod 17 having a handle 18 thereon. A nozzle 19 projects from the T 65 16 into the end wall of a casting 21, which casting is provided with a bottom 22 having an opening 23 at one end thereof. This opening enters a chamber 24 formed by an arched portion 26 integral with the casting 21. The arched portion 26 referred to terminates in an upwardly extending port or outlet 27 directly above which is a curved 70 baffle 28 suspended from the under side of a trough 31 and extending across the entire length of the casting 21 and being disposed directly beneath the retort pipe 13. At 32 and 33 I have shown burner plates slantingly disposed and supported upon the casting 21. These burner plates are provided with sawed slots for the passage of gas therethrough and are prevented from warping by tie pieces 34 and 36. At 37 I have shown 75 a tray disposed beneath the T connection 16 having the needle valve therein.

80 The operation of my device is as follows:—

The tank 7 is filled with a liquid fuel such as coal-oil and air pressure is placed on top 85 through the medium of the pipe 7. A little oil is now placed into the trough 31 and the tray 37 and ignited, which heats the retort pipe 13 and the T connection 16. I now open the valve 11 and allow the liquid fuel 90 to enter the retort 13 where it is immediately vaporized and passes to a needle valve located in the T connection 16. By now rotating the handle 18 the needle valve is opened and allows the atomized fuel to 95 enter the chamber 24. This produces an injector action which draws in a large amount of air through the opening 23 which mixes with this vaporized fuel. This mixture exhausts upwardly through the chimney 27 100 105 striking the baffle plate 28 thus filling the

2
entire interior of the casting 21. This gas will immediately escape through the sawed openings 32 and 33 and will become ignited from the burning fuel in the trough 31. By 5 constructing my retort and needle valve of a non-oxidizing metal as well as the burner plates 32 and 33, I am enabled to construct a burner which will have long life and one which does not become clogged through scale 10 formed by oxidation through contact with the fuel or the hot metal.

It is to be understood that the form of my invention herewith shown and described is to be taken as a preferred example of the 15 same, and that various changes in the shape, size and arrangement of parts may be resorted to without departing from the spirit of the invention or the scope of the subjoined claim.

Having thus described my invention, I 20 claim:—

In a burner, the combination with a casting having an orifice formed therein, of a chamber formed above said orifice and having an outlet therein, a baffle plate mounted 25 above the outlet of said chamber, burner plates movably secured on said casting and having a series of parallel slots formed therein, a trough formed above and between said burner plates, a retort pipe supported above 30 said trough, means for controlling the flow of fuel from said retort pipe to said chamber, and means for pre-heating said control means.

In testimony whereof I affix my signature. 35

LEMUEL P. COULTER
